CLAIM

The ornamental design for a body for nail clipper, as shown and described.

DESCRIPTION

FIG. 1 is a perspective view of a body for nail clipper embodying the design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a bottom plan view thereof with the jaws in the open position.

FIG. 7 is a bottom plan view thereof with the jaws in the closed position; and,

FIG. 8 is an enlarged right side elevational view showing the detail of the jaws.

The broken lines and unshaded areas adjacent to the broken lines define portions of the body for nail clipper that form no part of the claimed design.
